UNITED STATES PATENT OFFICE.

JOHN H. CARSON, OF GLENDALE, CALIFORNIA, ASSIGNOR OF ONE-THIRD TO SAMUEL C. CARTER, OF GLENDALE, CALIFORNIA, AND ONE-THIRD TO ANSON ROBINSON, OF LOS ANGELES, CALIFORNIA.

PUMP JACK.

Application filed December 7, 1925. Serial No. 73,735.

In this specification, and the accompanying drawing, I shall describe and show a preferred form of my invention, and specifically mention certain of its more important objects. I do not limit myself to the forms disclosed, since various changes and adaptations may be made therein without departing from the essence of my invention as hereinafter claimed; and objects and advantages, other than those specifically mentioned, are included within its scope.

My invention relates to means for pumping deep wells and the like, and among its more important objects are; first, to provide a device of this nature adapted for making very long pumping strokes; second, to furnish means for effectively counterbalancing the weight of the pumping rod and its attachments throughout its stroke; third, to supply means for partially counterbalancing the weight of pumped material supported by the pumping rod; and, fourth, to accomplish the foregoing by means of a simple and relatively inexpensive construction that is especially well adapted for its intended service.

My objects are attained in the manner illustrated in the accompanying drawing, in which—

Figure 1 is a side elevation of my invention with certain parts shown in section;

Figure 2 is an end elevation of the upper portion of the above construction when looking in the direction of arrow 2 of Fig. 1; and

Figure 3 is an enlarged detailed elevation of a portion of one of the equalizing bars of my invention, with its attachments; the view being shown partly in section.

Similar reference numerals refer to similar parts throughout the several views.

In the pumping of deep wells, as in the petroleum fields for instance, the weight of the pumping rod and its attachments plus the weight of the column of liquid being lifted thereby, is often enormous. Under such circumstances it is desirable to make the pumping stroke as long as possible to reduce the inertia losses due to reciprocating these great masses. It is also desirable to counterbalance the reciprocating masses throughout their strokes so far as this can be done, in order to further reduce the power required for pumping.

My invention as illustrated comprises a jack-shaft 4, rotatable in bearings 5 supported by a frame 6, and located over the casing head 7 of the well to be pumped. The jack-shaft has a plurality of sprockets 8 fixed thereon on each side of a central spur gear 9, which is also fixed to the shaft. Chains 10 engage the sprockets and the depending ends of the chains are respectively attached to a pair of equalizing bars 11 and 12. When more than one sprocket is used on each side of the central gear, the attachments of the chains to the equalizing bars is made yieldable, so as to place substantially the same duty upon each one of the chains. This may be conveniently accomplished, as shown, by employing clevis bolts 13 at the ends of the chains, and compression springs 14 surrounding the bolts between their nuts 15 and the equalizing bars. The clevis bolts are slideable in the bars and the springs therefore provide a resilient engagement between the chains and the bars. The tension on the chains may be equalized by means of nuts 15.

The pumping rod 16 is centrally hung from equalizing bar 11, and a counterweight 17 is centrally hung from equalizing bar 12. The counterweight preferably is slightly heavier than the combined weights of the pumping rod and its attachments, and weighs somewhat less than these combined weights plus the weight of the column of liquid being pumped. Consequently, if friction is not considered, power will have to be expended on the up-stroke of rod 16 only for lifting a portion of the weight of the column of liquid being pumped. On the down stroke of the pumping rod power will have to be expended only for lifting the unbalanced portion of the counterweight.

From a consideration of the above it will be apparent that the power expended on the up and down strokes may be very nearly equalized; and that the power consumed on both strokes is relatively very small since by far the greater portion of the weight being lifted in each case is counterbalanced by a descending weight.

To secure reciprocation of pumping rod 16 the jack-shaft 4 is rotated alternately in opposite directions. This is accomplished by means of a rack 18 at the end of connecting rod 19, the rack engaging the spur gear 9

and the engagement being maintained by means of an oscillatable yoke 20. The rack is adapted to slide longitudinally in the yoke and the variable angularity of the rack is taken care of by the pivoted engagement of the yoke on jack-shaft 4.

Connecting rod 19 is actuated by a crank pin 21 rotated by the large gear 22, and the latter is driven by pinion 23. The power for driving the pumping mechanism may be applied in any convenient manner to shaft 24 on which the pinion 23 is fixed.

From the foregoing description it will be apparent that a relatively small amount of power is required to operate my invention, since the weight of the pumping rod and its attachments is counterbalanced; and that, inasmuch as the pumping power is utilized on both strokes of the pumping rod, the power flow may be made substantially uniform. It will also be seen that any reasonably desired pumping stroke is easily obtainable and easily variable, as by changing the throw of crank pin 21 by relocating it in one of the holes 25.

A feature of my invention that greatly adds to its utility is the pivoted attachment of frame 6 to its base 26. The base is provided with upstanding plates 27 at the corners, and the upper frame is attached to these by means of bolts 28. By removing one pair of these bolts the other pair may be utilized as hinge pins for tipping the frame laterally. The tipping can be done by power if a pin is inserted through hole 29 in

yoke 20, and through a corresponding hole in rack bar 18. In this manner the structure above the casing head of the well may be quickly placed out of the way when the pumping rods, etc., have to be withdrawn. 40

Having thus fully described my invention, I claim:—

1. A device of the character described, comprising; a jack-shaft having a sprocket fixed thereon; a chain engaging said sprocket having depending ends respectively supporting a pumping rod and a counterweight; a gear fixed upon said shaft; a crank-pin rotatable in an orbit spaced from the gear in a plane parallel thereto; and a rigid bar 50 operatively connected at one end to said crank-pin and having a rack at its other end operatively engaging said gear, whereby said shaft may be rotated alternately in opposite directions by the orbital rotation of said 55 crank-pin.

2. A device of the character described comprising; a jack-shaft having a plurality of sprockets fixed thereon; a chain engaging each of said sprockets having depending ends; resilient attaching connections at each of said chain ends; a pair of equalizing bars respectively engaging the corresponding chain ends by means of said resilient connections; a pumping rod intermediately supported by one of said bars; a counterweight intermediately supported by the other said bar; and means for rotating said shaft alternately in opposite directions. 65

JOHN H. CARSON.
